PULL TAB FOR A TEAR STRIP OPENER

Vinson S. Potts, Cherry Hill, N.J., assignor to Crown
Cork & Seal Company, Inc., Philadelphia, Pa., a corpo-
ration of New York

Filed Apr. 6, 1964, Ser. No. 79,357

Term of patent 14 years

(Cl. D58—26)

FIGURE 1 is a top plan view of a pull tab for a tear strip opener embodying my new design wherein the apertured end thereof terminates in an edge formed by substantially straight converging portions which merge in a rounded juncture;

FIGURE 2 is a bottom plan view of the pull tab shown in FIGURE 1;

FIGURE 3 is a side elevational view of the pull tab shown in FIGURE 1;

FIGURE 4 is an end elevational view of the pull tab shown in FIGURE 1 taken from the right of FIGURE 1;

FIGURE 5 is an end elevational view of the pull tab shown in FIGURE 1 taken from the left of FIGURE 1;

FIGURE 6 is a longitudinal sectional view taken along the line 6—6 of FIGURE 1;

FIGURE 7 is a top plan view showing a modified form of my novel pull tab design which differs from the foregoing embodiment in that the apertured end thereof terminates in an arcuate edge; and

FIGURE 8 is a bottom plan view of the modified design shown in FIGURE 7.

I claim:

The ornamental design for a pull tab for a tear strip opener, as shown and described.
